UNITED STATES PATENT OFFICE.

WILLIAM L. PAUL, OF SOUTH BEND, INDIANA, ASSIGNOR TO OLIVER CHILLED PLOW WORKS, OF SOUTH BEND, INDIANA.

CULTIVATOR.

1,003,941.

Specification of Letters Patent. Patented Sept. 19, 1911.

Application filed February 15, 1910. Serial No. 544,125.

To all whom it may concern:

Be it known that I, WILLIAM L. PAUL, of South Bend, in the county of St. Joseph and State of Indiana, have invented certain new and useful Improvements in Cultivators; and I do hereby declare the following to be a full, clear, and exact description of the invention, such as will enable others skilled in the art to which it appertains to make and use the same.

This invention relates to improvements in cultivators,—the object of the invention being to produce a cultivator that will admit of easily and quickly raising the gangs either individually or as a pair and also adjusting them for depth relatively to each other or as a pair, and to so construct the mechanism that the results above mentioned can be attained with the use of a single lever and a single latch.

With this object in view the invention consists in certain novel features of construction and combinations of parts as hereinafter set forth and pointed out in the claims.

In the accompanying drawings, Figure 1 is a longitudinal sectional view partly in elevation of a cultivator embodying my improvements. Fig. 2 is a transverse sectional view partly in rear end elevation, and Figs. 3, 4, 5, and 6 are diagrammatical views.

1 represents an arch axle having journals at its respective ends mounted in carrying wheels 2 and upon said arch axle a frame 3 is mounted. In advance of the carrying wheels, a front arch 4 is supported by and depends from the cultivator frame 3, the depending arms of this arch being provided at their lower ends with laterally projecting members 5 with which the forward ends of plow gangs 6 are connected. The laterally projecting members of the front arch 4 are connected, by means of brace-rods 7 with the frame 3 preferably in proximity to the mounting of said frame upon the arch axle 1. A draft equalizer 8 is supported by the forward portion of the frame 3 in proximity to the tongue 9 and from respective ends of the evener bar 8, pivoted links 10 depend,—these links being connected

with the depending portions of the front arch by means of rods 11.

Somewhat in rear of the front arch 4, a rock shaft 12 is mounted and is provided at its respective ends with depending arms 13, 55 the latter being connected by means of rods 14 with the journals of the arch axle 1. Two brackets 15, 15, are mounted at respective ends of the rock shaft 12 and attached to the depending arms of said rock shaft. 60 The upper ends of the two brackets 15 are connected by a transverse bar 16 and this bar is provided centrally between its ends with a standard 17. An evener bar 18 is pivotally supported centrally between its 65 ends by the standard 17 and with respective ends of said bar the upper ends of rods 19 are pivotally connected,—the lower ends of said rods being connected with the respective plow gangs, as clearly shown in Fig. 1. 70

A lever 20 is secured to the rock-shaft 12 or to one of the arms 13 thereof and provided with a latch 21 having a tooth 22 which is normally pressed, by means of a spring 23, into engagement with a toothed 75 segment 24 secured to the cultivator frame 3 adjacent to the rock shaft 12. A rack-bar 25 is attached at its upper end to the evener bar 18 near one end of the latter and passes through a guide arm 26 secured to the lever 20. The rack-bar 25 is so disposed that it will be engaged by a tooth 27 on the latch 21.

It will be observed that the rock shaft 12, brackets 15 and cross-bar 16 constitute 85 a rocking frame and that the evener bar which is connected with the respective plow gangs is mounted upon and carried by this rocking frame.

When it is desired to raise one of the 90 gangs, the latch 21 will be operated by means of a latch lever 28 to disengage the teeth 22 and 27 from the racks 24 and 25, thus permitting the shaft 12 to be rocked by means of the lever 20 and the rocking 95 frame to be moved upwardly. The raising of the plow gangs will be controlled by foot pressure applied thereto by the operator and when the rocking frame is raised, as above explained, the gang upon which the least 100

amount of foot pressure is exerted will rise while the other gang will remain in its lowest position. The two gangs may be locked in such relative positions by the engagement of the tooth 27 or latch 21 with the rack 25. Should it be desired to adjust the one gang a trifle lower in the ground than the other, this may be accomplished by releasing the latch bar 21 from the rack 25 without moving the lever 20 and then pressing with the foot upon the gang to be lowered. The diagrams, Figs. 3-6 show approximately the relative positions of the evener bar and rock shaft under various conditions. In Fig. 3 the position of the parts are indicated which will occur when the gangs are down to cultivate at even depths, at which time the rods 19 which connect the evener bar 18 with the cultivator gangs will be disposed as indicated by the dotted lines.

In Fig. 4 the position of the parts are shown as when the gangs are both up and level. In Fig. 5 is shown the positions which the parts will assume when the right hand gang is down and the left hand gang is raised, and in Fig. 6 is shown the position of the parts when the right hand gang is raised and the left hand gang is down. It will be noticed that the arc traveled by the rock shaft is always the same and limited by the travel of the lever. It will also be noticed that when a single gang is raised, it travels twice the height that both would with the same stroke of lever and therefore the assisting force (either traction or a spring lift) will be always constant and equal to its load.

Having fully described my invention what I claim as new and desire to secure by Letters-Patent, is,—

1. The combination with two cultivator beams and a rock shaft, of evener means movable with the rock-shaft, connections between said evener means and respective cultivator beams and means for holding the rock shaft in position.

2. The combination with two cultivator gangs and a rock shaft, of a pivoted bar sustained by said rock shaft, connections between respective ends of said bar and the respective cultivator gangs and means for holding the rock shaft in position.

3. In a cultivator, the combination with a rock-shaft and cultivator gangs, of an evener bar pivotally supported between its ends by said rock-shaft, connections between the respective ends of said evener bar and the respective cultivator gangs and means for holding the rock shaft in position.

4. In a cultivator, the combination with a rock-shaft and cultivator gangs, of evener devices connecting said cultivator gangs

with the rock shaft, means for locking said evener devices at different adjustments and means for holding the rock shaft in position.

5. In a cultivator, the combination with a rock shaft and cultivator gangs, of evener devices carried by said rock-shaft and connected with said cultivator gangs, a lever for rocking the shaft, means for locking the lever, and means for locking the evener devices and the cultivator gangs at different adjustments.

6. In a cultivator, the combination with a main frame and two cultivator gangs, of a rock shaft, a pivoted bar mounted on said rock shaft, connections between respective ends of said pivoted bar and the respective cultivator gangs, a single lever for rocking said rock-shaft, a toothed segment on the main frame, a latch device on the lever to engage said segment, and means on the pivoted bar engaged by said latch device to lock said bar and the cultivator gangs in different adjustments.

7. In a cultivator, the combination with a frame and cultivator gangs, of a bar pivotally supported between its ends and having its respective ends connected with the respective cultivator gangs, means for raising or lowering said pivoted bar bodily, and means for locking said pivoted bar at different positions to which it may be rocked on its pivotal support.

8. In a cultivator, the combination with a frame and cultivator gangs, of a rocking frame, a lever secured thereto, an evener bar pivotally supported upon said rocking frame, rods connecting said evener bar with the cultivator gangs, a toothed segment secured to the main frame, a rack-bar attached to the evener bar, a latch mounted on the lever and having teeth to engage said toothed segment and rack-bar, and means for operating said latch.

9. In a cultivator, the combination with a main frame and cultivator gangs, of a rock shaft supported by the main frame, an arch axle supporting the main frame, wheels supporting said arch axle, connections between the arch axle and rock shaft, brackets secured to the rock shaft, a cross-bar connecting said brackets, an evener bar mounted on said cross-bar, connections between the evener bar and cultivator gangs, a ratchet bar attached to the evener bar, a toothed segment on the main frame, a lever connected with the rock-shaft, and a latch carried by said lever and adapted to engage the toothed segment and ratchet bar.

10. In a cultivator, the combination with a main frame and cultivator gangs, of a rock-shaft, an evener bar mounted on the rock-shaft, connections between the evener

bar and cultivator gangs, a lever secured to the rock-shaft, a toothed segment secured to the main frame, a rack bar attached to the evener bar, a guide arm for the rack bar secured to the lever and a spring pressed latch mounted on the lever and adapted to engage both the toothed segment and the rack bar.

In testimony whereof, I have signed this specification in the presence of two subscribing witnesses.

WILLIAM L. PAUL.
